ELECTRIC FLOOR LAMP

Filed Oct. 3, 1929

Inventor

HENRY S. SIEGEL

By Leckdelson
Attorney

UNITED STATES PATENT OFFICE

HENRY S. SIEGEL, OF PHILADELPHIA, PENNSYLVANIA

DESIGN FOR AN ELECTRIC FLOOR LAMP

Application filed October 3, 1929. Serial No. 32,927. Term of patent 3½ years.

To all whom it may concern:

Be it known that I, HENRY S. SIEGEL, a citizen of the United States, and a resident of Philadelphia, county of Philadelphia, State of Pennsylvania, have invented a new, original, and ornamental Design for Electric Floor Lamps, of which the following is a specification, reference being had to the accompanying drawing, forming a part thereof, wherein:—

Figure 1 is a perspective view of a lamp embodying the new design; and

Figure 2 is a side elevational view of the upper portion of the lamp taken at right angle to the view shown in Figure 1.

In the said accompanying drawing it will be observed that the lighting unit, which is supported by a standard or pedestal, comprises an upper vase-like member the upper end of which is open to permit light rays to be directed upwardly toward the ceiling, and a lower member of substantially inverted bell-shape within which a secondary source of light is housed. This lower member is of glass material, the external surface of which may be decorated.

I claim:

The ornamental design for an electric floor lamp as shown and described.

HENRY S. SIEGEL.
